UNITED STATES PATENT OFFICE.

JAMES GAYLEY, OF BRADDOCK, PENNSYLVANIA.

BLAST-FURNACE LINING.

SPECIFICATION forming part of Letters Patent No. 463,146, dated November 17, 1891.

Application filed July 28, 1890. Serial No. 360,227. (No specimens.)

To all whom it may concern:

Be it known that I, JAMES GAYLEY, of Brad-
dock, in the county of Allegheny and State of
Pennsylvania, have invented a new and use-
ful Improvement in Blast-Furnace Linings, of
which the following is a full, clear, and exact
description.

In constructing a blast-furnace the inclos-
ing walls have heretofore been made of a re-
fractory quality of fire-brick. In the lower
portion, commonly known as the "hearth" and
"bosh," it is of great importance that the
brick-work should be maintained as nearly as
possible to its original thickness, for as the
wear increases there is increased irregularity
in the conduct of the process which entails
greater expense; but in this portion the wear
is very rapid by reason of the chemical action
of the molten cinder, which, under the intense
heat, has a corrosive and destructive action
on the brick-work. The wear at the bosh I
have found to be especially injurious to the
action of the furnace. As the brick-work be-
comes corroded there is substituted, however,
through the nature of the reactions of the
blast-furnace process, a more refractory ma-
terial, composed largely of carbon, which to
some extent arrests this destructive action.
It is to this carbon coating that the endurance
of the hearth and bosh walls is due. I have
repaired walls that were originally thirty-six
inches thick where but six inches of the
original brick-work remained, which were
protected by such carbon coating of a thick-
ness of eighteen inches. When the furnace-
lining is new and before the carbon coating
can have had time to form, the deterioration
of the walls at the bosh and hearth is very
rapid, and during the work of the furnace the
character of the charge is apt to vary at times
and to produce a corrosive cinder of such
chemical nature as will eat away the natural
carbon coating and will attack the brick walls.
It has occurred to me that the furnace-walls
would be much better preserved if the natural
process of carbon deposit could be assisted
and supplemented by constructing the walls
of the hearth and bosh (and preferably also
the bottom of the hearth) of a strong and du-
rable material containing carbon in suitable
form. The difficulty of accomplishing this is
to secure graphitic material sufficiently strong

to resist the weight of the furnace-walls and
the scoring action of the stock as it descends
in the furnace. These difficulties I have over-
come by my invention, which consists in con-
structing the walls of the bosh and hearth of
brick compounded of refractory fire-clay and
graphitic carbon, such as the substances
known in commerce as "plumbago," "black
lead," and "graphite." The fire-clay forms a
bond for the carbon, giving the bricks the nec-
essary strength and durability to resist com-
pression and abrasion, while making it in the
form of bricks or blocks enables it to be built
in a strong and substantial manner in the
furnace-walls.

To make the bricks I prefer to proceed as
follows: In an ordinary pug-mill or dry-pan I
mix fire-clay and the graphitic carbon above
mentioned in proportions which may be from
twenty-five to fifty per centum of graphitic car-
bon and from fifty to seventy-five per centum
of fire-clay. The most desirable proportions
I have found to be about twenty-five per
centum of graphitic carbon and seventy-five
per centum of fire-clay, though my invention
is not limited to any special proportions of the
parts, which may be varied according to the
judgment of the skilled furnace engineer. 75
This compound I temper and mold into the
form of bricks suitable for building in fur-
nace-walls and burn them in the usual manner
in the manufacture of fire-brick, and in this
operation it will be found that no sensible 80
deterioration is caused by combustion of the
carbon. I then build these bricks in the in-
walls of the hearth and bosh of the furnace
and in the bottom of the hearth, for example,
so that they shall constitute eighteen inches, 90
more or less, of the thickness of the walls, and
in setting them I may use as a mortar a mix-
ture of fire-clay and carbon compounded sub-
stantially in the manner and in proportions
as above stated. The strength of the bricks is 95
such that they do not weaken the structure
of the furnace, and in their practical use I
have found them of great benefit in preserv-
ing the walls, and consequently in making the
work of the furnace uniform and economical. 100
When the furnace is first started into blast,
instead of presenting bare hearth and bosh
walls liable to be corroded by the cinder, the
carbon bricks resist this action of the cinder

and are themselves renewed and supplemented by the natural deposit of carbon in the furnace. The saving which I thus secure is very considerable and will be appreciated by those who practice my invention.

In making brick for the boshes I may substitute for the graphitic carbon other forms of carbon—such as pulverized anthracite coal, charcoal, or coke—though bricks thus made are not so strong or durable.

As an additional improvement I may add to the compound of which the bricks are made some lime or other basic material, such as magnesia, which may amount to about twenty 15 per centum or less of the whole mass if lime be used and five per centum or less if magnesia is used. This will render the bricks still more refractory and durable; but my invention, broadly considered, covers the bricks, 20 whether containing the basic material or not.

I claim—

1. A blast-furnace having in the in-walls of its bosh bricks containing refractory clay and carbon, substantially as and for the purposes described.

2. A blast-furnace having in the in-walls of its bosh and hearth bricks containing refractory clay and graphitic carbon, substantially as and for the purposes described.

3. A blast-furnace having in the in-walls of its bosh and hearth bricks containing refractory clay and carbon set in mortar of similar composition, substantially as and for the purposes described.

In testimony whereof I have hereunto set 35 my hand this 24th day of July, A D. 1890.

JAMES GAYLEY.
